US00D927325S

(12) **United States Design Patent** (10) Patent No.: **US D927,325 S**
(45) Date of Patent: **** Aug. 10, 2021**

(54) **WATCH**

(71) Applicant: **WITHINGS**, Issy-les-Moulineaux (FR)

(72) Inventor: **Thomas Droze**, Paris (FR)

(**) Term: **15 Years**

(21) Appl. No.: **35/509,798**

(22) Filed: **Jan. 16, 2020**

(80) **Hague Agreement Data**

Int. Filing Date: **Jan. 16, 2020**

Int. Reg. No.: **DM/207815**

Int. Reg. Date: **Jan. 16, 2020**

Int. Reg. Pub. Date: **Jul. 17, 2020**

(51) **LOC (13) Cl.** **10-02**

(52) **U.S. Cl.**

USPC **D10/32**

(58) **Field of Classification Search**

USPC D10/32, 39; D14/344; D11/3

See application file for complete search history.
